HAT EXPANDER

George Vlasis, Milwaukee, Wis.

Application July 25, 1949, Serial No. 106,512

9 Claims. (Cl. 223—25)

1

This invention relates to improvements in hat expanders, and more particularly to means for equalizing the expansion of the various hat engaging sections of the hat expander and means for adjusting said expansion in accordance with a hat size indicator.

In the hat renovating trade, it is the usual practice to employ an expandable former which is inserted interiorly of the hat band and which engages the hat with outwardly directed radial pressure. In this manner, the hat may be conveniently handled in the blocking, stretching or other renovating operations. The instant former preferably involves a four section construction, the outside periphery of the assembly providing a smooth oval contour capable of fitting the inside configuration of most hats without deformation thereof. In order to accommodate various sized hats, and to be useful as a hat stretcher, the former is made expandable. In a construction of this type, however, it is highly desirable that the oval peripheral form of the vice be maintained for all adjustments.

It is the principal object of this invention to provide equalizing guide means at the juncture of the adjoining hat engaging sections of the hat expander which will positively insure that the oval form assumed by the hat engaging sections for one adjustment will be substantially maintained in each other selected adjustment. It is a further object of the invention to provide an indicating means to facilitate the adjustment of the hat engaging sections to the proper and desired hat size.

Thus, it is an object of the invention to provide a hat expander which will, by positive action, maintain and equalize hat engaging sections in relatively perfect rigid oval alignment for any selected and visibly indicated hat size.

Other objects will be more apparent upon an examination of the following disclosures.

In the drawings:

Fig. 1 is a plan view of the hat expander, portions of the hat engaging sections being broken away to show details of the equalizing mechanism.

Fig. 2 is a cross sectional view of the indicating mechanism which is incorporated within the turnbuckle handle.

Fig. 3 is a cross sectional view taken along the line 3—3 of Fig. 1.

Fig. 4 is a cross sectional view taken along the line 4—4 of Fig. 1.

Like parts are identified by the same reference characters throughout the several views.

2

The expandable former comprises a pair of end sections 10 and a pair of side sections 11. These hat engaging sections may be made of wood, plastic or metal or the like, and have their peripheral surfaces so shaped as to present an oval hat engaging surface broken only at the juncture of the sections with one another. The contiguous portions of the sections are impositively joined by equalizers shown generally at 12 and which will be hereinafter described in more detail.

Two opposed sections 10 are provided with bores 9 in which are anchored axially aligned screws 15 and 16 which are held in place within the bores 9 by pins 17. Screws 15 and 16 each bear oppositely pitched threads and are in complementary threaded engagement with interiorly threaded turnbuckle handle 18. Manual rotation of the turnbuckle handle 18 will result in longitudinal extension or retraction of the screws 15 and 16, which motion is imparted to the end sections 10, and through the equalizers 12 to the side sections 11. The equalizers 12 are disposed obliquely with respect to the outer periphery of the sections at about forty-five degrees to the axis of the turnbuckle.

Each equalizer comprises a pair of telescopically related members. There is a sleeve 33 fixed in the socket 26 of the side member 11 and slideable freely into the somewhat larger bore 27 in the end element 10. Fixed in the socket 29 of end element 10 is a bar 30 freely slideable within the sleeve 33. The compression spring 35 seats against the end 36 of bar 30 and seats against the bottom of the socket 26 of the lateral element 11 of the expander. This structure is duplicated at each corner of the expander, it being immaterial, obviously, which of the expander elements carries the sleeve and which the bar.

In any case, only the sleeve is visible to the operator between the elements of the expander. The axis of relative telescopic movement between the bar and sleeve of the equalizer is desirably, although not necessarily, at an angle of forty-five degrees to the axis of the turnbuckle. At this angle, the sections of the expander tend to maintain their relative positions in all expansion and contraction of the end elements 10. At an angle greater than forty-five degrees, the equalizers will tend to increase the relative movement of the lateral elements 11 respecting the end elements 10, whereas at an angle of less than forty-five degrees, the lateral elements will have less relative movement than the end elements in the adjustment of the latter.

It is the function of the equalizers not only to effect in and out movement of the lateral elements in correspondence with the in-and-out movement of the end elements, but to regularize the movement of the side elements 11 and to prevent any of the elements from tipping or becoming misaligned respecting the others. For this purpose, it might be assumed that there should be a tight fit between the sleeves 33 and the bars 30, but an unduly tight fit between these parts causes binding which tends to produce irregularities of movement, rather than to prevent these. I have discovered that by using the compression springs to supplement such guidance as is provided by the relatively loose fit of the bars in the sleeves, great uniformity of movement is achieved with little or no tendency of the parts to bind. Thus, when the hat size is being enlarged, the spring 35, by pressure engagement with the end surface 36, will force the end and side sections apart in a uniform manner and prevent any binding of the slideable parts. As this action takes place at all four junction points of the side and end sections, a uniform equalization is effected. Also because of the use of the coil spring 35, clearances between the various sliding parts may be made smaller than heretofore possible and thus a more rigid and accurate positioning may be accomplished even at extended positions of the device.

In order that the operator may know at all times the exact hat size to which the expander is adjusted, the following construction is desirably employed.

The screws 15 and 16 are axially bored at 20 and 19 (see Fig. 2) respectively. An indicator rod 21 is fixed in bore 19 but is permitted to slide freely in bore 20. The turnbuckle handle 18 is provided with one or more apertures 22 whereby the operator may observe hat size indications which are engraved on the rod 21 as shown at 23 in Fig. 1. It has been found convenient to make the pitch of the screw threads such that one complete revolution of the turnbuckle handle 18 will result in a concentric change of position of the hat engaging sections equal to one hat size; hat sizes being accommodated ranging from six and five-eighths (6 $\frac{5}{8}$) to seven and seven-eighths (7 $\frac{7}{8}$).

From the foregoing description, it is seen that by the use of the illustrated equalizers, the relative alignment of the end and side sections 10 and 11 is substantially constant for all hat size positions. This is accomplished by means of a novel structure and organization of the equalizer elements whereby the adjacent hat engaging sections are under positive pressure produced by the spring 35. This construction prevents misalignment of the various sections by eliminating binding between the equalizer elements and permits smaller clearances between such elements and thus produces a more accurately guided adjustment. In addition, these advantages are further enhanced by the employment of a novel indicating device which enables the operator to predetermine and select the proper alignment of the various sections to accommodate the size of hat about to undergo renovation.

I claim:

1. In a hat expander having a turnbuckle including a pair of axially aligned and oppositely threaded screws having distal ends, an indicator comprising a calibrated rod fixed with respect to one of said screws, and a turnbuckle handle in complementary threaded engagement with each of said screws, the turnbuckle handle having an

internal bore in which the indicator rod is disposed and having a viewing aperture intermediate its ends through which the calibration of the indicator rod may be viewed.

2. The device of claim 1 wherein the axially aligned screws are each provided with bores, and wherein the calibrated rod is fixed in one of said bores and axially slideable in the other of said bores.

3. The device of claim 2 wherein the rod has a flattened portion intermediate its ends and upon which its calibrations appear.

4. The device of claim 1 in further combination with oppositely disposed expander end sections to which the distal ends of said screws are anchored, and oppositely disposed side sections in expansible connection with said end sections.

5. In a hat expander, the combination with end sections and side sections having adjacent ends provided with axially aligned oblique bores, of a sleeve fixed in one of said sections and having an end extending telescopically into the bore of the other, a bar fixed in said other section and reciprocable telescopically in the sleeve, and a compression spring within said sleeve and seated against said bar.

6. In a device of the character described, the combination with an end section of a hat expander and a side section of a hat expander, said

30 end section and side section being each provided with axially aligned oblique bores of different diameters, the section having the bore of larger diameter being provided with a shoulder and a bore of reduced cross section extending axially 35 beyond said shoulder and to a greater depth into the section, a bar seated into said bore of reduced cross section and extending appreciably into said bore of larger diameter, a sleeve seated into the bore of smaller diameter and in which 40 the bar is telescopically reciprocable, and a coil spring within said sleeve and bearing against said bar.

7. In a hat expander, the combination of a turnbuckle having a nut and oppositely pitched internal threads at the end portions thereof, axially aligned screws having proximate ends in complementary threaded engagement with the turnbuckle and extending from either end thereof and having distal ends anchored in expander

50 end sections whereby rotary turning of the turnbuckle nut will cause the end sections to move toward and away from each other, expander side sections disposed between said end sections and spaced therefrom, and equalizers spanning the spaces between end and side sections, whereby

55 motion of the end sections is equally and uniformly transmitted from said end sections to said side sections, causing them to move toward and away from each other complementary with like movement of the end sections, the adjacent 60 ends of said end and side section being provided with axially aligned oblique bores and each equalizer comprising a sleeve fixed in one of said bores and having an end extending telescopically into the other of said bores, a bar fixed in said 65 other of said bores and reciprocable telescopically in the sleeve, and a compression spring within said sleeve and seated against said bar.

8. The device of claim 7 wherein a size indicator comprising a calibrated rod is fixed in one of said turnbuckle screws and wherein the turnbuckle nut is provided with a viewing aperture through which the calibrations of the rod may be viewed.

75 9. The device of claim 7 wherein the axially

aligned turnbuckle screws are each internally bored, and a calibrated indicator rod is fixed in one of said screw bores and movable in the other screw bore, the turnbuckle nut being provided with a viewing aperture through which the calibration of the rod may be viewed.
